UNITED STATES PATENT OFFICE.

SOLOMON H. GOLDBERG, OF CHICAGO, ILLINOIS.

WATERPROOF ROOFING PRODUCT AND PROCESS OF MAKING THE SAME.

1,113,116.

Specification of Letters Patent.

Patented Oct. 6, 1914.

Application filed July 11, 1910. Serial No. 571,285.

To all whom it may concern:

Be it known that I, SOLOMON H. GOLDBERG, a citizen of the United States, residing in the city of Chicago, county of Cook, 5 and State of Illinois, have invented certain new and useful Improvements in Waterproof Roofing Products and Processes of Making the Same, of which the following is a specification.

10 This invention relates to improvements in waterproof roofing products and process of making the same, and has among its salient objects to provide a pre-formed product which is colored symmetrically with any 15 desired set of figures of one or more colors and in which the paint or pigments are intimately associated with the facing of the roofing; to provide a weatherproof roofing of the character referred to in which the 20 facing is generally granular in character, being formed of gravel, sand, minute pebbles, comminuted mica and the like; to provide an improved process of producing the product in which the tinting or coloring is 25 applied to the roofing concurrently with the manufacture of the same and as one step of a single continuous process; to provide a process by which the roofing may be tinted or colored with any desired design of a 30 single color or of variegated colors and in which the figures of the design may be formed symmetrically and with absolute accuracy; to provide an improved process of the character referred to in which the tinting or coloring is applied while the roofing 35 is still heated, thereby permitting the coloring to be more intimately associated and mixed with the facing of the roofing; to provide an improved process which can be 40 very economically carried out and in general to provide improvements of the character referred to.

The invention consists in the matters hereinafter described and more particularly 45 pointed out in the appended claims.

Referring to the single figure of the drawing, I have shown the upper face view of a portion of roofing made in accordance with my invention. This roofing preferably consists of a flexible foundation such as felt to which is applied a facing of gravel, sand or other comminuted material of a generally similar nature. In practice the felt or foundation material is run through a suitable 55 vat and saturated with a heated asphaltic solution and the gravel then applied. The

coated web is then run through suitable pressing rolls. While still in its heated condition the web of roofing is run through a pair of rollers, one of which is provided with 60 tinting or printing forms. The paint or tint applying form is provided with raised designs. The construction is such that the various designs are applied to the facing of the roofing symmetrically and accurately 65 and while the roofing is still in its heated condition. The nature of the facing is such that it can be much more accurately and effectively tinted or colored while in a heated condition and the tinting or coloring 70 matter also more effectively unites and mixes with the asphaltic solution with which the facing is mixed. It has been found in practice that the roofing so coated not only permits of a much more accurate design and 75 more possible variations in colorings and arrangements of the same, but also that such roofing can be manufactured at a relatively low cost. In addition the coloring will not run when subjected to weather exposure. 80

For purposes of illustration reference may be had to the accompanying drawing in which the single figure shows an upper face view of a portion of a roofing, the facing 1 of which is formed of screened gravel, which 85 is tinted with a plurality of designs symmetrically applied, a portion of the designs, as 2, being in red and another portion 3 in green.

I am aware that webs of stock of various 90 kinds have been heretofore provided with various designs, such as linoleums and also that heretofore a roofing has been provided with a pigment intimately associated with the facing. However, none of the prior 95 processes, as far as I know, have ever succeeded in producing a prepared roofing provided with colored designs, the designs being formed simultaneously with the formation of the roofing itself. 100

The invention is not limited to the details of ingredients specified except as set forth in the appended claims.

I claim as my invention:

1. The process of preparing ornamental 105 roofing, consisting in coating the surface of a flexible absorbent material with a hot bituminous binder, while said binder is heated applying a layer of granular material, and before said binder is cool applying a layer of paint in designs. 110

2. As a new article of manufacture a flex-

ible strip of roofing material comprising a foundation of pliable absorbent fabric, a bituminous water proof binder associated with the face of the fabric, a facing of granular material adhesively secured in place in the binder and having portions projecting above the surface thereof and a water proof coloring material applied to a plurality of fields or areas of the facing, contrasting

with the interposed spaces and forming 10 designs, said coloring material being intimately associated with the binder and forming a covering and an intimate union with the surfaces to which it is applied.

SOLOMON H. GOLDBERG.
